UNITED STATES PATENT OFFICE.

EDMUND P. KINNE AND HENRY BLANCHARD, OF ALLIANCE, OHIO, ASSIGNEES TO AMERICAN STEEL FOUNDRIES, OF NEW YORK, N. Y., A CORPORATION OF NEW JERSEY.

CONTOUR FOR COUPLINGS.

1,120,060.

Specification of Letters Patent.

Patented Dec. 8, 1914.

Application filed August 26, 1912. Serial No. 716,994.

To all whom it may concern:

Be it known that we, EDMUND P. KINNE and HENRY BLANCHARD, citizens of the United States, residing at Alliance, in the county of Stark and State of Ohio, have invented certain new and useful Improvements in New Contour for Couplers, of which the following is a specification.

Our invention relates to that class of car couplers known as the M. C. B. type which employ a pivoted knuckle, a lock therefor and a lifter for operating the lock; and more particularly relates to an improvement in the form of the outline or contour and the location of the hook or knuckle pivot pin center in relation thereto.

The principal objects gained by our improved contour are as follows:

First: increase of strength, (amounting to 41% over couplers constructed with the M. C. B. standard contour lines) through those sections defined by a straight line passing transversely through the knuckle pivot pin center. Experience has shown that a large portion of the failure of car couplers has been due to fracture through the lugs or ears of the coupler head and through the pivot pin hole of the knuckle.

Second: increase of strength of wall through that portion of head known as the "face of the coupler." Experience has also shown that a large proportion of the car coupler failures has been due to fracture of the metal at this location.

Third: greater ease in coupling, either on a straight track with couplers off of center line of cars or while cars are on short curves; ability for coupled cars having this improved coupler to turn curves of shorter radii.

Fourth: decreased liability of unintentional disengagement of mating couplers.

Fifth: increased length of useful life of car couplers having our improvements; experience has shown that many couplers reach the end of their usefulness by wearing out on the inner or pulling face of the hook or knuckle,—and at other bearing points, causing the distance from the face of the hook to the guard arm opposite to increase to such an amount as to allow two couplers to slip by one another, thus causing unintentional uncoupling. The object here gained is to provide such a shape as to increase the

period during which the permissible wear will take place.

Our invention will be more readily understood by reference to the accompanying drawings, wherein—

Figure 1 shows in full lines two car couplers having our improved contour, the dotted lines illustrating the standard contour; Fig. 2 shows two couplers of improved contour in engagement illustrating the extent of angular movement permitted; Fig. 3 shows a coupler of improved contour in full lines in engagement with a standard M. C. B. coupler, shown in dotted lines, and also illustrating in dot and dash lines the extreme angular movement permitted in such relation; Fig. 4 shows the normal coupled position of two improved couplers when the center lines coincide and also shows in dotted lines the position of maximum lateral displacement when center lines are parallel; and Fig. 5 shows the relation of a coupler having our improved contour when mated with a coupler of standard contour, center lines being parallel and displaced laterally until the guard arm of the M. C. B. coupler contacts the back of contour of improved coupler.

In Fig. 1, the dimension and radius lines have been applied to only one coupler to avoid confusion.

Referring to Fig. 1 it will be seen that the contour is constructed about the two center lines X—X and O—O set at right angles to each other. The method of construction is as follows: With radius "a" two arcs are drawn tangent to straight line Y—Y which passes through intersection of center lines X—X and O—O at an angle of 30° to line O—O; the centers from which these arcs are struck are placed "e" distance from line X—X. With radius "b" arcs "F" and "C" are struck from center located by dimensions "j" and "m" and "l" and "n" respectively. Arcs E and F and C and D are then joined by tangent straight lines. With radius "c" arcs are struck from centers located by dimensions "h" and "j" and by "i" and "k" and same are joined up with tangent straight lines to arcs F and C. Arc "C" whose center is determined by "i" and "k" is joined by a straight line tangent to it which passes through the point located by dimensions

"f," plus "u" and "v" to the arc passing through point located by dimensions "f" and "v" and which is struck by a radius "d'." Arc "H" is joined to arc struck with radius "s" from centers located by "r" and "q" by a straight line tangent to both arcs. Arc struck with radius "d" passes between points located by dimensions "p" and "q" and tangent to arc struck by 10 "s" at "I."

The first object as heretofore mentioned is attained by the addition to M. C. B. contour of amounts as indicated at point "C" and at point "I" whereby the transverse dimension through the lugs or ears of the 15 coupler head and through the pin hole center of the knuckle is increased; it is further accomplished by the location of the pivot pin hole center eccentrically with the arcs 20 describing the lugs of the head, this location is such that with the use of the standard M. C. B. knuckle pivot pin (1 $\frac{1}{8}$) the thickness of the wall from inner edge of pin hole to inner edge of contour at location 25 "C" exceeds the thickness of the wall from outer edge of pin hole to outer edge of contour at "I" by 21% and affords an increase of 41% in the moment of inertia (referred to pin hole center) of this transverse section 30 through the pin hole center over the similar moment of inertia of a coupler constructed on the lines of the M. C. B. Association and with the pivot pin hole located concentrically with the arc defining the lugs of 35 the head; this is illustrated by Fig. 1, where it will be seen that "X" dimension for the improved contour exceeds a corresponding or "y" dimension for the M. C. B. contour and that the pin center for the improved 40 contour is located "t" distance from the center from which arc is struck by radius "Z¹," defining the ears or lugs of the coupler head, while the center for the pin hole with the M. C. B. contour is located at the 45 same point as center for generating arc struck by radius "Z²" to define the ears of coupler heads having the M. C. B. contour lines. Experience has shown that a large proportion of the knuckles and bars break 50 from the pin hole inwardly to inner edge of the contour and to eliminate this and all other breakage of knuckle and head at this general location is the object gained.

The second object is attained by an addition, as indicated at point "B," to enable a thicker face wall to be obtained and thus eliminate the breakages at this point; experience shows that failures of car couplers at this location have been very frequent; it 60 is to be noted that this increase is obtained without change in the relative position between the coupling face (inner curve of knuckle contour) and lock of the coupler.

The third object is attained by, first, reducing the length of the point of the knuckle

by removing metal as indicated at "F" to increase the transverse dimension from point of guard arm to point of knuckle, (w—Fig. 1) to enable the mating coupler to enter the recess between knuckle and 70 head more readily and, second, by the combination of the changes as indicated at points A, D, F, and G, to enable a like improved coupler mating to take a position of maximum angle to 16 $\frac{1}{4}$ ° as compared 75 with 15 $\frac{1}{2}$ ° for two mating couplers of the M. C. B. standard contour lines.

The fourth object is attained by metal added at location "H" which causes this portion of the closed knuckle of a mating 80 improved coupler to come in contact with the guard arm of its mate after a lateral displacement less by 3/32" than the lateral displacement obtained with two mated couplers of the standard Master Car Builders' 85 Association lines, (the measurement in this case being 9/16" while in the case of two new improved couplers it is 15/32"), this is illustrated by Fig. 4 and it will be seen that this greatly reduces the liability to become 90 disengaged from the mating coupler.

The fifth object is attained, first; by an addition of an amount at location "E" which affords this increased amount of metal as additional material to be worn away 95 before such an opening between point of knuckle and guard arm (minimum measurement) is reached that will condemn the coupler from further service, for experience has shown that it is at this location where 100 the greatest amount of wear to the contour takes place. This object is secondly accomplished by removing from location "D" an amount of metal exactly equal to that amount added at location "E" so that the angle which the short tangent straight line joining arcs struck with radii "a" and "a" makes with center line O—O is increased to 30°; by means of this increased slope (greater depth to the reentrant curve) there 110 is caused increased liability for two improved couplers when mated to wear toward each other, thus transferring the point of greatest wear inwardly and increasing the length of useful life of the coupler; this construction has the further advantage that it assists to reduce the liability for couplers to become uncoupled unintentionally as it 115 is evident that the increased "hook" shape at this portion of the contour will tend to hold couplers together. By referring to Fig. 4 it will be seen how this increased hook shape as formed by arcs E—D and D—E are of such shapes as to draw two mating couplers together until their center lines coincide.

Having shown how the above mentioned objects are accomplished a further object of our improvement is that the improved couplers of the contour described herein couple 120 125 130

interchangeably with perfect freedom with
couplers of the standard Master Car Builders'
Association contour lines as is evident
from Figs. 3 and 5, and also couple with
5 couplers having the standard Master Car
Builders' Association contour lines in such
a manner that the liability to become uncoupled
is reduced as compared with two couplers of M. C. B. lines.

10 We claim:

1. A car coupler knuckle, the contour or outline of which includes arcs "D", "E", "F", "H" and "I", joined by certain straight lines, substantially as shown and described.
- 15 2. A car coupler, the contour or outline

of which includes arcs "A", "B", "C", "D", "E", "F", "H" and "I", joined by certain straight lines, substantially as shown and described.

20 3. A coupling head, the contour of which includes arc "A", arc "C" struck from centers located by dimensions "i" and "k" and joined by a tangent straight line, and that arc struck by "d" which passes between points located by dimensions "g" and "p", substantially as shown and described.

EDMUND P. KINNE.
HENRY BLANCHARD.
